METHOD AND APPARATUS FOR
RECLAIMING SHEET METALCharles D. Crouse and John F. Marshall, West
Alexandria, Ohio, assignors to Porcelain Strip
Mills, Inc.

Application February 26, 1938, Serial No. 192,828

2 Claims. (Cl. 29—81)

This invention relates to a method and apparatus for reclaiming sheet metal and particularly to reclaiming the metal content of porcelain enameled sheets.

Owing to the rapidly increasing use of porcelain enameled sheet metal parts in the manufacture of furniture and household appliances, such as refrigerators, cook stoves, cupboards, cabinets, etc., and the fact that the process of applying the porcelain cover to sheet metal is sufficiently difficult to result in a considerable number of imperfectly covered parts which are not permitted to be used in the finished product, it is becoming a difficult problem to dispose of the rejected material.

Ordinarily, metal parts rejected in manufacture are accumulated and remelted for use in the manufacture of new sheets, but sheets having a porcelain enamel coating are not usable in this manner, first because of the deleterious effect on the furnaces in which they must be melted, and second because of the influence the porcelain has on the remelted metal itself.

Due to the fact that the process of coating sheet metal with porcelain enamel comprises fusing the vitreous coating and the metal sheet together, it has up to this time been found impractical to remove all of the enamel at the low cost necessary to warrant the operation in view of the metal salvaged thereby, with the result that manufacturers of porcelain sheet metal products have either resorted to the expedient of hauling this rejected scrap over long distances to places where it was acceptable as filling for low ground, or of purchasing land adjacent the manufacturing plants, where the price was not prohibitive, for permanent use as a dumping ground.

It is therefore an object of this invention to provide a simple and inexpensive method which will completely remove a porcelain coating which is fused to a sheet of metal.

It is another object to provide simple and inexpensive apparatus to carry the method into effect.

In the course of experimentation to evolve a suitable method of carrying the object of this invention into effect, it was found that although bending a plurality of waves in the sheet at short intervals, a given spot being bent first convex then concave, had a considerable influence in removing the porcelain coating, a greatly improved result was had when the same process was repeated on the sheet with the waves made to extend at right angles with respect to the first waves.

Further experimentation, however, disclosed that a vastly improved result was attained when the surface of the sheet was stretched to a considerably larger area than its original area, whereby the grain of the metal itself was expanded so as to release the tentacles of the porcelain which were imbedded therein.

The method may therefore consist in one or more of a plurality of steps comprising bending, stretching, or bending and stretching of the sheet to remove the porcelain, and the apparatus may comprise a means for carrying out several or all of the steps mentioned, preferably in a continuous cycle. One embodiment of such apparatus is now disclosed, reference being made to the accompanying drawing, wherein

Fig. 1 is a top plan view of the apparatus.

Fig. 2 is a longitudinal vertical section taken at 2—2 of Fig. 1.

Fig. 3 is a fragmentary section taken at 3—3 of Fig. 2 showing the corrugating surfaces of two of the rolls.

Similar numerals refer to similar parts throughout the several views.

Construction

25

In the drawing the frame 10 carries a series of journal boxes in which pairs of rolls are rotatably supported. The first pair comprising the rolls 14 and 16 are smooth round rolls, without grooves or corrugations, rotatable in journal boxes 18 and 20 and geared together to rotate in unison by a pair of duplicate gears 22.

The second pair, comprising rolls 24 and 26, each has axially spaced grooves 28 extending circumferentially around it, the grooves of one of the pair meshing into the ridges 26 which separate the grooves of the other. This pair is rotatable in the journal boxes 30 the two rolls being geared together to rotate in unison by the pair of duplicate gears 32. In the drawing part only of the rolls 24 and 26 are shown provided with the grooves 28 and ridges 26 but it will be understood that in practice these rolls are provided for their entire length with grooves like those shown.

The third pair comprising rolls 34 and 36, each has a series of circumferentially spaced grooves 38 extending lengthwise of the roll parallel to its axis of rotation forming an equal number of teeth 40 between the grooves, the teeth of one of the pair meshing into the grooves of the other. This pair is rotatable in the journal boxes 44 the two rolls being geared together by the duplicate gears 50 to cause them to rotate at the same speed.

35

40

45

50

55

While the drawing shows grooves 38 and teeth 40 covering part only of the circumference of the rolls it will be understood that the entire circumferences of the rolls 34 and 36 are provided with 5 these grooves and teeth.

The fourth pair comprising rolls 52 and 54 are substantially duplicates of the second pair 22 and 24, except that they may preferably be slightly larger in diameter and the total number of 10 ridges 28 may be several more or several less in the length of the rolls 52, 54 than in the rolls 22, 24 so that the spacing may be different in one pair than in the other. They are rotatable in 15 journal boxes 56 and geared to rotate together by the duplicate gears 60. The fragmentary cross section Fig. 3 shows how the ridges 28 of one roll fit into the grooves 26 of the other.

Gears 20, 32, 50, and 60 are drivably connected by idler pinions 64, 66, and 68. Secured to the 20 pinion 64 to revolve therewith is the large gear 70. A pinion 72 having rotative bearing in the hub 74 meshes with the large gear 70. A pulley 76 is secured to the pinion 72 to rotate therewith. Any suitable source of power, none shown, 25 may be belt connected to pulley 76 to drive the rolls, the arrangement being such as to cause all of the rolls to revolve in the same direction.

A pair of wire scratch brushes 78 and 80 are 30 rotatable in journal boxes 82. These brushes should preferably revolve much faster than the rolls and are therefore provided with small pulleys 86 which may be belted to a suitable source 35 of power. Adjusting screws 88 are provided to adjust the rolls for different thicknesses of sheets and for different pressures therebetween. A table 90 is provided to support the sheets in a horizontal position when starting them through the first pair of rolls.

Operation

40 The porcelain coated sheets to be reclaimed are laid on the table 90 and started between the first pair of rolls 14 and 16. Since a great many enameled sheet metal parts are drawn or otherwise formed to curved surfaces, these rolls operate principally to flatten out the sheets before they reach the second pair of rolls. It will therefore be understood that when the machine is being operated exclusively on sheets which are already flat, the first pair of rolls are preferably 45 removed and the sheets initially fed into the second pair of rolls.

As a sheet passes through the second pair of rolls, the grooves and ridges 26, 28 of the rolls, 55 form a series of alternate ridges and furrows in the sheet. Due to the pressure between the rolls and the resulting friction between the rolls and sheet, the sheet does not get appreciably narrower. It follows that, after the sheet has passed through these rolls, while the linear measurement 60 from edge to edge of the sheet remains at the original dimension, the actual surface measurement across the sheet when following the cross sectional contour down into the furrows and up over the ridges has been greatly increased by 65 stretching the metal.

The sheet next passes through the third pair of rolls 34, 36 which corrugates it crosswise. This has the effect of partially removing the longitudinally extending ridges and furrows previously made and the further effect of slightly 70 widening the sheet. It also bends a given spot in the metal in a different direction than that in which it was bent by the first rolls.

The slightly widened sheet next passes through the fourth pair of rolls 52, 54 which again stretches the metal crosswise to again provide the longitudinal ridges and furrows. If the rolls 52, 54 have been made slightly larger in diameter 5 than the rolls 22, 24, the tendency will be to stretch the metal somewhat lengthwise of the sheet. If the grooves 26 and ridges 28 of rolls 52, 54 have been spaced slightly different from the grooves 26 and ridges 28 of the rolls 22, 24, the 10 metal will be more apt to be bent at different points when passing through rolls 52, 54 than it was when previously passing through rolls 22, 24. The furrows now extend in the right direction to have the completely loosened and broken up 15 porcelain brushed out by the rotating scratch brushes 78, 80.

It will of course be understood that in cases where one side of the sheet stock only needs to be cleaned, one brush may be removed, or, when 20 the need for thorough cleaning is not so great, both brushes may be omitted. The first pair of rolls 14, 16, as before stated, may be removed when all of the sheet stock being run is already substantially without curved surfaces. Furthermore 25 it would be practicable where a low priced apparatus was desired, and the quantity of stock to be reclaimed was relatively small, to use apparatus containing one pair of rolls as 22 and 24 and a second pair 34 and 36 without any of the 30 other rolls whereby the sheets would be bent and stretched into furrows and ridges first in one direction of the sheet then in a direction at right angles to the first direction, or, the single pair of rolls 22, 24 could be used alone if the sheets were 35 run first lengthwise, then crosswise through such rolls.

Any other apparatus which operates to remove the porcelain by increasing the surface area of the sheets or by bending the sheet or by a combination of both bending and stretching is considered within the spirit of the claims to the apparatus herein set forth, and any method comprising bending, stretching, or a combination of the two within the spirit of the method claims 15 which follow.

We claim:

1. The method of salvaging the metal content from porcelain coated metal sheets which consists of pressing a series of ridges and furrows in 20 the sheet, next forming similar ridges and furrows crosswise of the first, next forming similar ridges and furrows crosswise of the second, the last said ridges and furrows being of different spacing from the first, whereby the porcelain is 25 broken loose from the metal, separating the porcelain and metal then removing the broken porcelain by scratch brushing the sheet lengthwise of the last made furrows.

2. Apparatus for removing an enamel coating 30 from a metal sheet, said apparatus comprising, in combination, a series of rollers to press separate series of furrows one after the other in the sheet as it passes therethrough, each series being crosswise of that next preceding, to thereby loosen 35 the enamel, and a rotatable scratch brush positioned to brush the sheet in the same direction as the last made furrows, whereby both the tops and bottoms of the furrows are brushed to remove 40 the loosened enamel.
